UNITED STATES PATENT OFFICE

2,086,059

DITCHER

Charles Akerblade, Hawk Springs, Wyo.

Application March 25, 1936, Serial No. 70,882

2 Claims. (Cl. 37—98)

The present invention relates to a ditcher and has for its prime object to provide means whereby a ditch may be dug by a machine of varying depths through the proper manipulation of convenient and reliable means.

Another important object of the invention resides in the provision of a ditcher of this nature which is comparatively simple in its construction, inexpensive to manufacture, thoroughly efficient and reliable in use, convenient and compact in its arrangement of parts and otherwise well adapted to the purpose for which it is designed.

With the above and numerous other objects in view as will appear as the description proceeds, the invention consists in certain novel features of construction, and in the combination and arrangement of parts as will be hereinafter more fully described and claimed.

In the drawings:—

20 Figure 1 is a top plan view of a machine embodying the features of my invention.

Figure 2 is a side elevation thereof.

Figure 3 is a front elevation thereof.

25 Figure 4 is a vertical detail section taken substantially on the line 4—4 of Figure 1.

Referring to the drawings in detail it will be seen that numeral 5 denotes the digging nose, the upper edges of which merge into an isosceles triangular plate 6 and the ends of which merge 30 into rearwardly diverging wings 7 the rear ends of which taper downwardly as at 8 into a terminal point.

Now referring to the means for supporting the digging element and the adjustments incident thereto. Numeral 9 denotes what I call a caster wheel mounted on an axle 10 supported in an inverted U-shaped structure 11 the lower ends of which are curved rearwardly as shown to advantage in Figure 4. The bight or cross portion 40 has a bolt 12 extending therethrough with a bearing sleeve 14 on the lower portion thereof. A U-shaped bracket has its cross portion 15 provided with an opening to receive the upper end of the bolt and its uprights have a bolt 16 extending 45 therethrough for rockably supporting an elongated beam 17. Links 18 connect the forward end of the beam 17 with bars 19 the rear ends of which are curved as at 20 and the terminals of which are secured as at 21 with the wings 7. 50 Numeral 23 denotes a hitch bar with suitable apertures 24 therein and braced as at 25 and 26 with respect to the rods 19 and also braced with respect to the beam 17 by pivoted links 28.

Numeral 29 denotes a cross member between 55 the rear portion of the wings 7 and rising there-

from are bars 30 between which the beam 17 extends. A stop pin 31 is mounted between the upper extremities of the rods 30. A removable pin 32 is mounted intermediate the ends thereof above the beam 17 and may be removed to lower 5 the nose end of the digging element.

A shaft 35 is journaled in bearings 36 mounted on the rear portions of the wings 9 rearwardly of the member 29 and has cranks 37 on the ends thereof terminating in trunnions 40 on which are 10 journaled wheels 41. This shaft has fixed thereto a lever 42 cooperable by a suitable detent mechanism with a bracket 43 fixed as at 44 with the cross member 29 so that the rear end of the digging element may be adjusted up or down as may 15 be required.

It is thought that the construction, operation, manipulation and advantages of this invention will now be quite apparent to those skilled in this art without a more detailed description thereof. 20

The present embodiment of the invention has been described in considerable detail merely for the purposes of exemplification since in actual practice it attains the features of advantage enumerated as desirable in the statement of the 25 invention and the above description.

It will be apparent that changes in the details of construction, and in the combination and arrangement of parts may be resorted to without departing from the spirit or scope of the 30 invention as hereinafter claimed or sacrificing any of its advantages.

What is claimed is:—

1. A ditching machine comprising a V-shaped plow member including a nose and having wings 35 diverging rearwardly from the nose, a shaft rockably mounted on the rear of the wings, cranks on the extremity of the shaft carrying wheels whereby the rear end of the plow may be raised or lowered by the movement of the shaft, a wheeled support including an upstanding bracket positioned near the apex and behind the nose of the plow, an elongated beam fulcrumed on the bracket in a manner to be unbalanced and having a portion extending forwardly of the nose of the plow, connecting arms at one end rockably connected with the forward end of the beam and at their other ends to the forward portion of the plow, the connection of the arms and beam disposed in a manner to carry the greatest weight forwardly, and means for connecting the rear end of the beam to the rear end of a wing so that movement of the rear end of the plow relative to the ground causes a reverse 45 50 55

movement at the forward end whereby the one adjustment regulates the nose of the plow.

2. A ditching machine comprising a V-shaped plow member including a nose and having wings diverging rearwardly from the nose, a shaft rockably mounted on the rear of the wings, cranks on the extremity of the shaft carrying wheels whereby the rear end of the plow may be raised or lowered by the movement of the shaft, a wheeled support including an upstanding bracket positioned near the apex and behind the nose of the plow, an elongated beam fulcrumed on the bracket in a manner to be unbalanced and having a portion extending forwardly of the nose of the plow, connecting arms at one end rockably con-

nected with the forward end of the beam and at their other ends to the forward portion of the plow, the connection of the arms and beam disposed in a manner to carry the greatest weight forwardly, and means for connecting the rear end of the beam to the rear end of a wing so that movement of the rear end of the plow relative to the ground causes a reverse movement at the forward end whereby the one adjustment regulates the nose of the plow, and means carried by the rear portion of the plow and coacting with the shaft to raise and lower the plow relative to the ground.

CHARLES AKERBLADE. 15
